UNITED STATES PATENT OFFICE.

ROBERT S. GRAHAM AND WILLIAM B. SAVELL, OF NEWARK, NEW JERSEY.

DESIGN FOR A KEY-TOP.

SPECIFICATION forming part of Design No. 23,197, dated April 17, 1894.

Application filed March 14, 1894. Serial No. 503,643. Term of patent 14 years.

To all whom it may concern.

Be it known that we, ROBERT S. GRAHAM and WILLIAM B. SAVELL, citizens of the United States, and residents of Newark, in the county of Essex and State of New Jersey, have invented a certain new and useful Design for Rubber Key-Tops, of which the following is a specification.

Figure 1 is a side view of a key-top showing our design. Fig. 2 is a plan view; these two views being deemed necessary to fully illustrate our design.

Our invention relates to rubber key tops, and it consists of the design substantially as herein shown and described.

a is the body of the key-top which is cylindrical or approximately cylindrical in general contour, but has a crease *b* substantially

as represented in the figures. This crease is located near the lower end of the cylinder, ²⁰ thus presenting to the eye the appearance of or approximating to a cylindrical outline interrupted near one end by an encircling crease or depression.

We claim—

The design for a key top substantially as shown and described. ²⁵

Signed at New York, in the county of New York, and State of New York, this 2d day of March, A. D. 1894.

ROBERT S. GRAHAM.
WILLIAM B. SAVELL.
